CLAIM

The ornamental design for a cover assembly for a patient support, as shown and described.

DESCRIPTION

The file of this patent contains at least one drawing executed in color. Copies of this patent with color drawing(s)/photographs(s) will be provided by the Office upon request and payment of the necessary fee.

FIG. 1 is a top view of a cover assembly for a patient support.

FIG. 2 is a right side view of the cover assembly for a patient support.

FIG. 3 is a left side view of the cover assembly for a patient support.

FIG. 4 is a front side view of the cover assembly for a patient support.

FIG. 5 is a top front, right side, perspective view of the cover assembly for a patient support.

FIG. 6 is a back view of the cover assembly for a patient support; and,

FIG. 7 is a bottom view of the cover assembly for a patient support.
